DESIGN FOR A CLASP

William F. Haas, Rockaway, Long Island, N. Y.

Application December 19, 1932. Serial No. 46,520

Term of patent 3½ years

To all whom it may concern:

Be it known that I, WILLIAM F. HAAS, a citizen of the United States and resident of Rockaway, L. I., in the county of Queens and State of New York, have invented a new, original, and ornamental Design for a Clasp, of which the following is a specification, reference being had to the accompanying drawing, forming part thereof.

Fig. 1, is a plan view of a clasp, showing my new design.

Fig. 2, is a side view thereof.

I claim:

The ornamental design for a clasp, as shown.

WILLIAM F. HAAS.
